BLOCKING PRESS

Evarts G. Loomis, Newark, N. J.

Application July 12, 1941, Serial No. 402,138

4 Claims. (Cl. 18—16)

This invention relates to presses, and more particularly to the type known as "blocking presses" in which various kinds of material are compressed into blocks or cylindrical sections to facilitate handling or subsequent converting of such materials. One of the materials compressed by an apparatus of this character is nitro-cellulose which, because of its characteristics, requires careful handling and treatment.

One of the objects of the invention is to provide a blocking press, which is preferably, but not necessarily hydraulically operated, in which a material such as nitro-cellulose is effectively compressed into cylindrical sections or blocks; which will operate with a minimum consumption of power; which will permit easy loading and removal of the material, and which will be of relatively simple construction.

Another object of the invention is to provide an improved closure means by which the cylinder within which the material is compressed is closed, said closure means being preferably hydraulically opened when required and permitting easy filling of the cylinder and the removal therefrom of the compressed material.

In the accompanying drawing, forming a part hereof, Fig. 1 is a vertical sectional view through a blocking press constructed in accordance with the invention, the view being taken on the line 1—1 of Fig. 3, looking in the direction of the arrows; Fig. 2 is a plan view of the cover or closure for the top of the press, the same being shown in closed position; and Fig. 3 is a top plan view of the press, with the cover in open position.

In the drawing, 1 indicates the lower cylinder of the press, the same containing a vertically reciprocable ram 2, provided at its lower end with the piston 3 having packings 4, confined by the plate 5 secured to the piston by the screws 6. The lower end of the cylinder 1 is closed by the threaded plug or nut 7 having packing 8, and provided with the passage 9 leading through it and into the cylinder, a pipe 10, leading from a source of hydraulic pressure, being connected to passage 9 whereby the hydraulic liquid under pressure may, when required, enter the cylinder 1 and operate against the lower end of piston 3 to raise the ram.

At its upper end, the cylinder 1 is provided with a head 11, formed with four upwardly and radially extending arms 11, having their upper ends secured by the screws 12 to a radially extending flange or plate portion 13 near the lower end of

5 the upper cylinder or compression chamber 14 of the press. The plate 13 is formed with ends 15 which are supported upon beams 16 or other supports for the press. Secured by screw 17 to the upper end of the shaft of the ram 2, is the head 18 of the ram, the same being adapted to be reciprocated vertically within the upper cylinder or compression chamber 14. The head 18 is provided with a suitable packing ring 19 secured in place by means of the screws 20. The upper end of the lower cylinder 1 is closed around the shaft of the ram 2 by means of a stuffing box consisting of the nut 21 and packings 22.

10 Material to be compressed within the cylinder or compression chamber 14 is placed within said chamber through the open top of the same, said top being normally closed by means of a pair of co-operating segmental cover sections 23 and 24 which, when the cover is in its closed position as 15 shown in Fig. 2, are brought together in edge abutment as at 25. These cover sections are 20 opened or closed by means of operating mechanism shown at the upper right in Fig. 1, the same including a cylinder 26 supported in bracket 25 30 and within which a piston 27 is vertically reciprocable to swing the cover sections toward or away from one another. The upper portion of the piston 27 is provided with two opposite-thread helical gear sections 28 and 29, the lower gear section 28 engaging gear thread 31 formed internally in a bushing 32 secured within the hub 33 of the cover section 23, while the gear section 28 on the piston engages with the gear thread 34 on the interior of the bushing 35 secured within the hub 36 of the cover section 24. The bushings 32 and 35 are respectively held within the hubs against axial movement by means of the rings 37 and screws 38. A closure cap 39 is fitted over the top of hub 36.

35 It will be apparent that when the piston 27 is moved upwardly by hydraulic pressure entrant into the cylinder below the piston 27 through pipe 40, the piston will be raised, and the upward movement of the same will cause the oppositely threaded gear sections 28 and 29 to swing the cover sections 23 and 24 apart to the positions shown in Fig. 3, thus uncovering the top or open end of the cylinder 14 and permitting compressed 40 contents of the cylinder to be raised and removed and a fresh batch of the material to be placed in the cylinder. As long as the hydraulic pressure is maintained in cylinder 26 to the piston elevated, the cover sections will remain open.

45 The lower end of the piston 27 carries a pack-

ing 41 and projecting downwardly from said lower end of the piston and through fixed packing 42 and cylinder closure cap 43, is a threaded stem or rod 44 carrying a spring-seat 45 vertically adjustable on rod 44 by the nuts 46 and 5 52. Coil spring 47 is located between the seat 45 and the cylinder closure cap 43, the pressure of said spring being adjusted by shifting the position of the spring seat 45. When the hydraulic pressure in cylinder 26 is released, spring 10 47 will cause the piston 27 to be lowered, and the descent of the piston will cause the cover sections 23 to be swung to closed position, as shown in Fig. 2, through the medium of the helical gearing previously described. It will thus be clear that by 15 the imposition and release of hydraulic pressure in cylinder 14, the cover sections can be opened and closed in the manner described. To prevent the material being compressed from being forced out between the cover sections during the compression of the material in cylinder or compression chamber 14, a cover disk 48 is placed in the cylinder on top of the material. This disk is loosely placed within the cylinder. The cover sections 23 and 24 fit securely at the top of cylinder 14 since their respective edges are shaped 20 to fit around the laterally projecting flange 49 formed at the top of cylinder 14, as clearly seen in Fig. 1.

Briefly, the operation of the blocking press 30 is as follows:

With hydraulic pressure imposed on the piston 27, the piston is held in elevated position, compressing the spring 47 and through the medium of the gearing 28, 29, 31 and 34, holding the cover sections 23 and 24 apart or in open position. The cylinder 14 is now filled with the material to be compressed and the cover disk 48 is placed in the cylinder on top of the material. Then, hydraulic pressure in cylinder 26 is released and the spring 47 will force the piston 27 downwardly and through the medium of the gearing 28, 29, 31 and 34 will swing the cover sections toward one another to closed position, shown in Fig. 2. Hydraulic pressure is now caused to enter the lower cylinder 1 through passage 8 and the same exerting upward pressure against the bottom of piston 3 on ram 2, will elevate the ram and cause the same to move upwardly so that the head 18 rises in cylinder 14 and the material in the cylinder 14 will be compressed between the head 18 of the ram and the closure means at the top of the cylinder. When the material has been compressed sufficiently, the hydraulic pressure in cylinder 1 may be reduced to thereby reduce the pressure of the material against the closure means 23, 24 and 48, and then hydraulic pressure is introduced into cylinder 26 to cause piston 27 to be elevated and open or spread apart the cover members 23 and 24. Hydraulic pressure through passage 8 is now increased sufficiently to cause the ram 2 to be again elevated sufficiently to raise the compressed material in block form out of the open top of the cylinder 14 where it becomes accessible for removal.

For forcing the ram 2 downwardly to its lowered position, hydraulic pressure is introduced through the top portion of cylinder 1 through passage 58 connected to piping 51 extending from a suitable source of hydraulic pressure.

From the foregoing, it will be seen that I have provided a press of greatly simplified construc-

tion by which various materials such as for example, nitro-cellulose or other materials which must be handled with care, may be compressed rapidly and safely without loss or waste of material. The means provided for automatically opening and closing the cover conserves the time and effort of the workmen in filling the compression chamber and removing the compressed blocks of material therefrom. Numerous other advantages following from the construction described will be apparent to those skilled in the art and it will also be obvious that various changes in structure may be made without departing from the spirit of the invention.

What I claim is:

1. In a press, a cylinder in which material is compressed, a ram movable in said cylinder, a cover against which the material is forced by the pressure of the ram, said cover comprising several segmental sections having edge portions in abutment and when in such abutment covering and closing the end of the cylinder, a movable piston, means for shifting said piston in one direction to cause the cover sections to be moved apart to uncover the end of the cylinder, means for moving the piston in an opposite direction to cause the cover sections to be brought together to close the end of the cylinder, and driving means interposed between the piston and said cover sections.

2. In a press, a cylinder, a cover for closing one end of said cylinder, said cover consisting of a pair of segments normally in abutment to extend over and close the end of the cylinder, said segments being pivotally mounted whereby they may be swung toward or away from one another, gearing for simultaneously swinging the segments toward or away from one another, a piston for operating said gearing, hydraulic means for shifting the piston in one direction and spring means for shifting it in the opposite direction.

3. In a press, a cylinder, a cover therefor, said cover consisting of several segments co-operatively closing an end of the cylinder, each of said segments having a hub portion, a piston movable through the hub portions of the segments, said piston and hub portions being provided with gearing by means of which the segments are moved away from one another on movement of the piston in one direction and brought together in abutment when the piston is moved in an opposite direction, and means for reciprocating the piston.

4. In a press, a cylinder, closure means therefor comprising a cover consisting of two segments, spring means for normally holding said segments in abutting relationship to co-operatively close an end of the cylinder, said segments each having a hub, said hubs overlying each other and being internally threaded, a piston extending through the hubs and provided with oppositely threaded portions and having its threads in engagement with the internal threads within the hubs, said threaded engagement being such that the segments are moved in opposite directions or away from one another to thereby uncover the end of the cylinder when the piston is moved in a direction to oppose the pressure of said spring means.

EVARTS G. LOOMIS.
